GUN MOUNTING

Richard C. Coupland, United States Army,
Norfolk, Va.

Application March 6, 1940, Serial No. 322,532

4 Claims. (Cl. 89—37)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to a gun mounting.

The purpose of this invention is to provide a gun mounting in which a recoil and counter-recoil mechanism is associated with a gun which has a flexible mounting, that is, a mounting in which the gun is mounted solely on trunnions whereby it is free to be manually moved in elevation. Mounts of this character are provided for aircraft and anti-aircraft machine guns which are to be pointed at rapidly moving targets.

A further object is to provide a mounting which may be readily adapted to an existing machine gun without seriously modifying the existing gun structure or necessitating the provision of a subcradle.

The invention is characterized by a cradle which is trunnioned at its rear end on a support and, has a two-point sliding connection with the gun, and also by the association of the cradle with resilient recoil, counterrecoil and buffer means carried by the gun barrel or the barrel jacket.

The specific nature of the invention as well as other objects and advantages thereof will clearly appear from a description of a preferred embodiment as shown in the accompanying drawing in which:

Fig. 1 is a view in side elevation of the improved gun mounting;

Fig. 2 is an enlarged fragmentary view in side elevation with parts in section;

Fig. 3 is a sectional view on the line 3—3 of Fig. 2.

Referring to the drawing by characters of reference the gun mount comprises a yoke A, a cradle B mounted in the yoke at its rear ends by means of trunnion pins C—C and a gun D carried by the cradle.

The cradle comprises a pair of spaced parallel side plates 5—5 connected by longitudinally spaced bottom plates or bars 6—6. The front extremities of the side plates are connected to a ring 7 which is adapted to encircle the barrel of the gun. The side plates are provided with aligned slots 8—8 for slidably receiving the ends of a bolt 9 which passes through an opening in the trunnion block 10 of the gun.

The trunnion block 10 forming part of the receiver frame of the gun, is of standard construction and includes a forwardly projecting cylin- 55

drical part 11 which is spaced from barrel 12 which in the case of a Browning gun is movable relative to the receiver frame. The part 11 is threaded both externally and internally to respectively attach a trunnion adapter 13 and a bearing 14 for the breech end of the barrel. A locking pin 15 threaded in the part 11 engages the bearing 14 and in the standard gun it also engages the barrel jacket 16 which is a relatively thin member extending to the muzzle of the barrel and spaced therefrom by a front bearing 17.

In modifying a standard gun to receive the mounting of this invention the rear portion of the barrel jacket is cut off at 18 and replaced by a short relatively heavy jacket 19 which is integral with the bearing 14 and includes a flange 20 for engaging the front face of the part 11. The front extremity of the rear jacket 19 is externally threaded to receive a coupling collar 21 which bears on the rear portion of the front jacket 16 and is connected thereto in any convenient manner, for example by welding indicated at 22. The collar 21 is locked to the jacket 19 by means of a set screw 23 and plug 24, which engages the threads on the jacket.

The ring 7 of the cradle slidably encircles the jacket 19 and its front and rear faces comprise seats for adjacent ends of a pair of springs 25 and 26 which also encircle the jacket. The front end of the front spring 25 seats against a washer 27 supported by the collar 21 while the rear end of the rear spring 26 seats against a washer 28 supported by the flange 20 and the trunnion adapter 13. Adjustment of the springs may be effected by advancing or retracting the coupling collar 21 which is fixed to the jacket 16.

The ring 7 and bolt 9 provide a two-part connection between the gun D and cradle B so that these parts maintain their relationship when the gun is moved vertically by rotating it about the trunnion pins C—C. When the gun is fired it moves rearwardly relative to the cradle, compressing the front spring 25 and enabling the rear spring 26 to be extended. The return stroke of the gun under influence of the front spring 25 is checked by the rear spring 26, a slight overtravel being permitted.

While the invention has been illustrated in connection with a gun having a movable barrel it is to be understood that it may equally well be applied to a gun with a fixed barrel.

I claim:

1. In a gun mounting, a gun including a receiver frame and a movable barrel, a rear barrel jacket connected to the frame, a front barrel

jacket separate from the rear jacket, a coupling member on the front jacket and threadedly connected to the rear jacket, a cradle having a ring encircling the rear jacket, a front spring between the ring and the coupling member, a rear spring between the ring and the receiver frame, said cradle having aligned slots in opposite sides, a bolt in the receiver frame of the gun inserted through the aligned slots and having longitudinal sliding movement therein, and means for pivotally mounting the cradle in rear of its connections with the gun.

2. In a gun mounting, a gun including a receiver frame and a movable barrel, a rear barrel jacket connected to the frame, a front barrel jacket separate from the rear jacket, a coupling member on the front jacket and threadedly connected to the rear jacket, a cradle having a spring seat engaging the rear jacket, a front spring between the seat and the coupling member, a rear spring between the seat and the receiver frame, means for slidably coupling the gun to the cradle in rear of the spring seat, and means for pivotally mounting the cradle at its rear end.

3. In a gun mounting, a gun including a re-

ceiver frame and a movable barrel, a rear barrel jacket connected to the frame, a front barrel jacket separate from the rear jacket, a coupling member on the front jacket and threadedly connected to the rear jacket, a cradle having a spring seat engaging the rear jacket, a front spring between the seat and the coupling member, a rear spring between the seat and the receiver frame, means for slidably coupling the gun to the cradle in rear of the spring seat.

4. A gun comprising a gun frame and a gun barrel unit mounted therein, a cradle, means on the cradle receiving the gun barrel unit for reciprocation thereof, with respect to said cradle, means on the cradle rearward of the first-mentioned means, receiving a portion of the gun frame for reciprocation thereof with respect to said cradle, spring means on opposite sides of said first-mentioned receiving means located for operation in the axial direction of the gun barrel unit, means on the gun fixing the outer ends of the springs with respect to the gun and means for pivotally mounting the cradle rearward of both of said receiving means.

RICHARD C. COUPLAND.
